(57) CLAIM

The ornamental design for a knife handle, as shown and described.

DESCRIPTION

FIG. 1 is a perspective view of the knife handle of the present invention;

FIG. 2 is a top plan view of the knife handle of FIG. 1;
FIG. 3 is a side elevation of the knife handle of FIG. 1;
FIG. 4 is a butt end view of the knife handle of FIG. 1; and,
FIG. 5 is the forward end of the handle which receives the knife blade.

The broken lines shown in the drawings are for illustrative purposes only and form no part of the claimed design.
